UNITED STATES PATENT OFFICE.

MAX UNGAR AND EDWARD S. BECKER, OF NEW YORK, N. Y.

DESIGN FOR A TOY STORE.

48,766.

Specification for Design.

Patented Mar. 21, 1916.

Application filed December 3, 1913. Serial No. 804,545. Term of patent 8½ years.

To all whom it may concern:

Be it known that we, MAX UNGAR and EDWARD S. BECKER, citizens of the United States, and residents of the city of New York, borough of the Bronx, in the county of Bronx and State of New York, have invented a new, original, and ornamental Design for a Toy Store, of which the following is a specification, reference being had to the accompanying drawing, forming part thereof.

Figure 1 is a front perspective view of the

toy store illustrating our new design. Fig. 2 is a vertical transverse section of the toy store.

We claim:—

The ornamental design for a toy store, as shown.

MAX UNGAR.
EDWARD S. BECKER.
